[57] CLAIM

The ornamental design for a grappler, as shown and described.

DESCRIPTION

FIG. 1 is a top and front perspective view of a grappler showing my new design;

FIG. 2 is a fragmentary sectional view taken along line 2—2 of FIG. 1, of one side of a tine of the grappler;

FIG. 3 is a fragmentary bottom plan view thereof with the stopping plate attached;

FIG. 4 is an enlarged perspective view of the interior walls of the grappler;

FIG. 5 is a bottom plan view thereof without stopping plate attached; and,

FIG. 6 is a top and rear perspective view thereof.

FIG. 1

FIG. 2

FIG. 3**FIG. 4**

FIG. 5

FIG. 6
